UNITED STATES PATENT OFFICE.

MYRTLE MAXWELL, OF LOS ANGELES, CALIFORNIA, ASSIGNOR TO ROY A. BAKER, OF LOS ANGELES, CALIFORNIA.

DESIGN FOR A HOSIERY-DISPLAY FIXTURE.

Application filed April 17, 1922. Serial No. 1,810. Term of patent 3½ years.

To all whom it may concern:

Be it known that I, MYRTLE MAXWELL, a citizen of the United States, residing at Los Angeles, county of Los Angeles, and State of California, have invented a new, original, and ornamental Design for a Hosiery-Display Fixture, of which the following is the specification, reference being had to the accompanying drawing, forming a part thereof, in which the figure is a perspective of the fixture.

I claim:

The ornamental design for a hosiery display fixture substantially as shown.

MYRTLE MAXWELL.
